UNITED STATES PATENT OFFICE.

EDWIN LUNN MILLER, OF SCRANTON, PENNSYLVANIA.

DESIGN FOR A BADGE.

SPECIFICATION forming part of Design No. 21,899, dated October 18, 1892.

Application filed August 25, 1892. Serial No. 444,114. Term of patent 14 years.

To all whom it may concern:

Be it known that I, EDWIN LUNN MILLER, a citizen of the United States, residing at Scranton, in the county of Lackawanna, in the 5 State of Pennsylvania, have invented and produced a new and original Design for a Badge, of which the following is a specification.

The object of this design is to provide a novel, handsome, and ornamental badge; and 10 the leading feature thereof resides in a badge having representations of leaves and provided with a field or shield bearing a cross.

The design is illustrated by the accompanying drawings, in which—

15 Figure 1 is a plan view of the badge, and Fig. 2 is a central sectional view of the same. In the drawings, the letter A indicates a base

or background formed by the face of the badge, and B indicates the representations of leaves. At the center is a field or shield C, 20 bearing a cross D.

The design provides a handsome badge which presents an ornamental and characteristic appearance to the eye.

What I claim is—

25 The design for a badge, substantially as shown and described.

In testimony whereof I have hereunto set my hand in the presence of two subscribing witnesses.

EDWIN LUNN MILLER.
